United States Patent Office

Des. 193,863
Patented Oct. 16, 1962

193,863

GARDEN TOOL HANDLE

Burton P. Franklin, Danville, Va., assignor to H. K. Porter Company (Delaware), Danville, Va., a corporation of Delaware

Filed Oct. 11, 1961, Ser. No. 67,072

Term of patent 14 years

(Cl. D35—2)

FIGURE 1 is a plan view of a garden tool handle showing my new design;

FIGURE 2 is an enlarged rear perspective view; and

FIGURE 3 is a side elevational view.

I claim:

The ornamental design for a garden tool handle, substantially as shown.
